UNITED STATES PATENT OFFICE.

RUSSELL LLOYD WREN, OF JEFFERSON CITY, MISSOURI.

ATTACHMENT FOR TOILETS.

Application filed February 4, 1929. Serial No. 337,363.

My invention relates to a device adapted to be used in conjunction with toilets, which I have denominated "Relaxative" by which name my invention will be known in the trade.

The object of the invention is to provide a device of this character which will enable one to comfortably recline against the same and which will perform a therapeutical function by maintaining the posture of the body in such a manner that the lower bowel is straightened and put in a more vertical position, hence evacuation of the bowels is materially aided; all as will be hereinafter more particularly specified and claimed.

Referring to the accompanying drawings, which are made a part hereof, and on which similar reference characters indicate similar parts,

Figure 1 is a side elevation illustrating one application of my invention,

Figure 2 is a similar view with the parts in a different position, and with parts broken away,

Figure 3 is a bottom plan view of a seat having my invention applied thereto, and

Figure 4, a side elevation illustrating the device applied to a toilet having no lid and supported from a supply pipe.

In the drawings reference character 10 indicates the base of a toilet having a hinged seat 11 and a hinged lid 12, all of which are of conventional construction. The lid 12 is shown elevated in Fig. 1, lowered in Fig. 2, and is omitted in Fig. 4.

My invention consists in the application of a body 13 to the bottom or under side of the lid 12 in a manner to bear against the small of the back of an individual just above the hips when seated upon the toilet.

While I have shown the device in Figs. 1 and 2 attached to the under side of the lid 12, as shown in Fig. 4 the body 13 may be supported in any other desired manner, or if desired, may be formed integrally with the lid 12.

The body 13 is provided with sides 15 which may be flat as shown, or any other desired shape, and a relatively broad curved surface 16 of a sufficient width to form a comfortable support for the back, and yet the device is of a size capable of being disposed when in inoperative position in a position depending through the seat 11 in the bowl of the base 10. On the under surface 55 of the body at each end of the same is secured a strap 17 provided with a longitudinal

slot 18 for the accommodation of a screw or other fastening element 19 for securing the body in adjusted position longitudinally of the lid 12.

In Fig. 4 I have shown a different style of toilet which does not have a lid, such toilet being supplied with a water pipe 20 upon which I mount the body 13 by means of a bracket 14 having a clamp 14' at its lower end, which may be adjusted vertically of the pipe 20 for varying the position of the body 13.

In considering what has been done heretofore along this line, I am aware that efforts towards sanitation and special comfort have been made, including the provision of foot rests, back rests, arm rests and the like, as well as the provision of toilet chairs having pivoted backs and other features for rendering them comfortable to the user. However, the provision of a solid body which is not a cushion and which is curved to fit snugly in position against the back of a person reclining against the same is an important novel feature of the present invention.

My device, or "Relaxative", may be made of any desired material, preferably however corresponding to the material of which the toilet seat and lid are constructed; for example wood, hard rubber composition, or the like material, or of light metal such as for example aluminum, and may be either made separately as shown, or formed integrally with the lid. By the use of my device certain therapeutic advantages are obtained which while not readily apparent are recognized by members of the medical profession, and while my device enables one to comfortably recline against the same it causes the body to assume a position such that the lower bowel is straightened and placed in a substantially vertical position; hence evacuation is materially assisted, constipation and piles are prevented, and the habit of correct posture is formed.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. An attachment adapted to be associated

with toilets for supporting the back of a person reclining against the same and for promoting the evacuation of the bowels, comprising a body having a substantially rigid back engaging surface of substantially semi-cylindrical formation conforming to the longitudinal curvature of the back for supporting the same in a comfortable position, and means for supporting said body in a position to contact with the small of the back of a person seated on said toilet, substantially as set forth.

2. An attachment for toilets comprising a body of substantially semi-cylindrical formation adapted to be supported in relation to the toilet seat in a manner to engage the small of the back of a person reclining

against the same when seated on the toilet, the semi-cylindrical surface of said body being substantially non yielding, and adjustable connections at each end of the semi-cylindrical surface of said body for securing the body to the under side of the hinged lid of a toilet whereby the lid may be closed when the toilet is not in use and in such position the body will be held suspended within the bowl through and in spaced relation to the seat, substantially as set forth.

In witness whereof, I have hereunto set my hand at Jefferson City, Missouri, this 31st day of January, A. D. nineteen hundred and twenty-nine.

RUSSELL LLOYD WREN.
